United States Patent Office

Des. 210,230

Patented Feb. 20, 1968

210,230

DESSERT DISH

Fernando Alvarez, Glen Dale, W. Va., assignor to Fostoria Glass Company, Moundsville, W. Va.

Filed June 26, 1967, Ser. No. 7,605

Term of patent 14 years

(Cl. D36—2)

FIG. 1

FIG. 2

FIG. 3

FIG. 1 is a side elevation of a dessert dish showing my new design with portions broken away;

FIG. 2 is a top plan view thereof; and

FIG. 3 is a section taken substantially along the line 3—3 of FIG. 1.

I claim:

The ornamental design for a dessert dish, as shown.
